ABSTRACT

A winch having an inertia responsive brake, and a velocity responsive actuator means also disposed in actuating relation to the said brake, wherein the actuator means is, at least to some extent, inertia responsive.

WINCH BRAKING MECHANISM

This application is a continuation of application, Ser. No. 800,654, filed Feb. 19, 1969, now abandoned.

BODY OF APPLICATION

This invention relates to cable winches and will be described in connection with suspended staging, although the invention has wider application.

At present, it is common practice, in winch operated suspended staging, to provide braking means to prevent too rapid descending movement of the staging. This braking means has been inertia responsive, and thus is not responsive to the velocity of the drum. Thus, if for any reason, rapid acceleration of the drum fails to cause actuation of the braking means, damage and injury can result. In addition, if the descending velocity of the staging can attain an undesirable magnitude without the acceleration exceeding the safety limit, this could also cause damage and injury.

It is a main object of the present invention to provide velocity responsive braking means for a winch, and particularly a velocity responsive actuator to actuate the inertia brake in the event it is not otherwise actuated, and to aid the inertia responsive means to actuate said brake.

Another object is to provide a velocity responsive actuator which, at least to some extent, is inertia responsive.

Various other objects of the invention will be apparent from the following description taken in connection with the accompanying drawings wherein:

FIG. 1 is a perspective view of a suspended staging incorporating the concepts of the present invention;

FIG. 2 is an enlarged fragmentary vertical sectional view taken along line 2-2 of FIG. 1 showing the braking end of the drum;

FIG. 2A is a fragmentary sectional view taken along line 2A-2A of FIG. 1;

FIG. 3 is a fragmentary end elevational view taken in the direction of the arrows 3-3 of FIG. 2 and on a scale smaller than that employed in FIG. 2;

FIG. 4 is a vertical sectional view taken along lines 4-4 of FIG. 2, FIG. 4 being on the same scale as FIG. 3;

FIG. 5 is a fragmentary vertical sectional view taken along lines 5-5 of FIG. 2, FIG. 5 being taken on the same scale as FIGS. 3 and 4;

FIG. 6 is a fragmentary sectional view taken along line 6-6 of FIG. 5, FIG. 6 being on a slightly enlarged scale as compared to that in FIG. 5;

FIG. 7 is a sectional view taken along line 7-7 of FIG. 2;

FIG. 8 is a sectional view taken along line 8-8 of FIG. 7; and

FIG. 9 is a midsectional view through a modified form of the actuator.

FIG. 1 shows a platform or staging 11 suspended by cables 13 alongside a building 15. Each cable is reeled in or payed out under the control of a motor-driven winch unit 17. Each winch unit is of the same construction and is shown as having an electric motor 19, although the motor could be hydraulic, internal combustion, etc. The motor is operated by controls (not shown) to drive a winch drum 31 via a speed reduction unit 33. Each drum 31 has an inertia brake which is designed to halt rotation of the drum, and thus halt descending movement of the platform 11, anytime the rate of descent exceeds a predetermined safe rate.

FIG. 2 shows, in section, the braking end of the winch drum. The drum has a drive shaft 35 which is supported by bearings, which in turn are mounted on horizontal members of the frame 41 of the winch unit 17. One of the bearings is shown in FIG. 2 and is labeled 43, and the associated horizontal frame member is labeled 45.

The drum 31 includes a hollow core member 51 which is mounted at its left hand end (as the parts are shown in FIG. 2) on the hub portion 53 of the broke housing 55. The left hand end of the housing is closed by a support plate 57 which has three lugs 59 (FIGS. 2 and 3) fitting in holes in the frame

member 45. The lugs hold the support plate 57 stationary relative to the winch drum 31 (and thus stationary relative to the brake housing 55 which is a part of the drum).

The inertia brake includes a plurality of annular rotary disks

5 71 (FIGS. 2 and 4) which are keyed to the housing 55 by keys 73 (FIG. 4), and a plurality of interleaved stationary disks 75, which have square holes 77 (FIG. 4) to non-rotatably fit on a square disk support 79. The latter is secured by bolts 81 (FIGS. 2 and 4) to the support plate 57.

10 The inertia brake includes a mechanism which is responsive to a predetermined accelerating movement of the winch drum 31 to force the disks 71 and 75 into tight frictional engagement, whereby they halt rotating movement of the drum. This mechanism includes a pressure plate 91 (FIG. 2) which is

15 equipped with a plurality of pins 93, which are surrounded by compression springs 94, and slidably project through an actuating plate 95. Retainers 96 are provided on the inner ends of the pins. Plate 95 is threadedly mounted on an actuating screw 97 which is secured to the drive shaft 35 of the drum 31.

20 It is evident that whenever the drum 31 accelerates, the actuating plate 95 will tend to remain stationary, thus creating relative rotary movement between the plate 95 and the screw 97. This movement causes outward threading movement of the plate 95 along the screw 97 to compress the springs 94 which, through pressure plate 91 urge the pressure plate into engagement with the interleaved disks 71 and 75 to compress the same.

25 However, there is a retarding spring 101 (FIGS. 2 and 5) which functions to prevent such outward threading movement of the actuating plate 95 until the rate of acceleration exceeds a predetermined safe limit. This spring is secured at one end to a lug 103 (FIGS. 5 and 6) on actuating plate 95 and is secured at its other end to a lug 105 (FIGS. 5 and 2) on an adjustment arm 107. The arm is secured to the brake housing 55 in a manner to be presently described.

30 The spring 101 urges the lug 103 to remain against a lug 108 (FIG. 5) which is carried by the brake housing 55. Thus the spring normally causes the actuating plate 95 to follow the movement of the drum 31 so long as the acceleration rate is below a predetermined limit. Whenever such limit is exceeded, the inertia of the plate 95 causes it to overcome the spring resistance and thread along the screw 97 and cause braking contact between the disks 71 and 75.

35 The arm 107 turnably fits on the drive shaft 35 (FIG. 2) but is held in a selected position of adjustment by a bolt 109 which threads through the brake housing 55 and fits in one of plural holes 110 (FIG. 5) formed in the arm 107. Thus the acceleration safety limit at which the plate will operate can be adjusted by varying the stress on the spring 101.

40 An auxiliary brake actuator is provided to actuate the brake, if for any reason, the inertia forces do not actuate the plate 95. In addition, this brake actuator is responsive not only to inertia forces but also to the velocity of the drum. Thus if the acceleration is small but steady, the velocity could build up to an objectional value. The auxiliary actuator will cause brake actuation prior to the platform reaching a dangerous descending velocity. The auxiliary brake actuator will, however, not prevent normal operation of the suspended platform.

45 The auxiliary actuator is best shown in FIGS. 2 and 3 and comprises a centrifugal friction brake. The brake includes a shoe 111 (FIGS. 2 and 7) which is mounted by a pivot 113 on a rotary shoe carrier 115 for movement toward a brake drum 117 under the influence of centrifugal force. The brake proper will be described more in detail presently.

50 The shoe carrier 115 is driven in the following manner. It is fixed to the lower end of a shaft 121 (FIG. 2) which is mounted by bearings 123 in a gear box housing 125. The housing 125 and drum 117 are shown as being portions of a one-piece casting, the drum being closed by a cover 126 and the box by covers 127 and 128. The carrier shaft 121 carries a bevel pinion 129 engaging a drive bevel gear 130. The latter is

55 fixed to the outer end of a shaft 131 which is mounted by bearings 133 carried by a tubular support member 134 and

has a pinion 135 formed on its inner end. The pinion meshes with the teeth of a ring gear 137 (FIG. 2A) which is bolted to the actuating plate 95. It is pointed out that the rotor shaft 131 passes inwardly of the rotary disks 71 (FIG. 2), but passes through aligned holes 139 formed in the fixed disks 75.

Referring now to FIGS. 7 and 8, the shoe 111 is of obtuse angular form having tang-like contact portion 111a disposed in a clevis portion 145 of the shoe carrier 115. The shoe also has a lobe portion 111b which acts as a weight to urge the contact portion 111a against the drum 117 when the lobe portion is subjected to centrifugal force. The carrier has a bulging portion 115a which acts to counterbalance the weight of the lobe 111b so that there is minimum vibration caused by the rotation of the carrier and its shoe.

A tension spring 151 urges the shoe 111 inwardly against a stop screw 153. The spring has one end hooked over a pin 155 carried by a clevis portion 111c of the shoe 111 and its other end hooked through a hole in the outer end of an adjustment arm 157. The arm extends into a clevis portion 115b of the carrier and is there mounted on a pivot 159. The position of the arm (and thus the magnitude of the tension exerted by the spring 151) is determined by a screw 161 which is threaded into the carrier 115 and held in place by a jam screw 163.

The stop screw 153 threads into the carrier and is held in a desired position of adjustment by a jam screw 165. The carrier 115 may be retained on the shaft 121 in any manner. A set screw 167 is shown in FIG. 7, the screw being held in place by a jam screw 169.

OPERATION

Let it be assumed that for some reason the platform descends at a rate beyond the predetermined safe limit. Normally, the actuating plate of each winch will, because of its inertia, (aided by the inertia of the driven parts of the brake) thread outwardly to compress the associated disks 71 and 75 and halt the descent. However, should, for any reason, the plate 95 not move outwardly as it should under the influence of inertia forces, the increasing speed of the carrier 115 (which is indirectly driven by the winch drum) will create sufficient centrifugal force to cause the contact portion 111a of the shoe to engage the drum 117. The resulting frictional drag will create a reverse driving force to drive the plate 95 outwardly. Thus the disk brake will be actuated by the auxiliary actuator.

It is pointed out that the jam-set-screw arrangement shown in FIG. 7 is merely illustrative and other means for obtaining the same results can be utilized. In fact, instead of two set screws, we contemplate utilizing only a single set screw coated with a commercially available fluid locking agent which hardens when the set screw is threaded into place to resist movement of the set screw. The counterweight portion 115a of the carrier 115 can be cut away to provide access to the single screws.

MODIFIED FORM OF INVENTION

FIG. 9 shows a modified auxiliary actuator in the form of a magnetic eddy current device. The device comprises two rows of permanent magnets 181 carried by a rotor 183 which is mounted on the outer end of a shaft 131a for rotation within a steel rotor housing 185. The housing is closed by a cover plate 186 and is mounted on the outer end of a tubular support 187 which may be identical to support 134 of the first form of the invention. The shaft 131a is supported within support 187 and would be in driving engagement with the ring gear 137 in the same manner as is shaft 131.

The operation of the modified form is as follows: Should the velocity of the winch drum become excessive (without sufficient acceleration to actuate plate 95) the rotor will be driven by the ring gear 137 at such a speed that the eddy currents in-

duced in the rotor housing will create a sufficient drag on the rotor to overcome the resistance of the spring 101 and cause outward movement of plate 95 and actuation of the disk brake of the winch.

Having described the invention in what is believed to be the preferred embodiment of the same, it is desired that it be understood that the invention is not to be limited other than by the provisions of the following claims.

We claim:

1. In a braking system for a winch drum, a shaft drivingly connected to said drum, a flywheel,

means providing a rotary connection between said flywheel and said shaft and urging said flywheel to rotate with said shaft but responsive to a predetermined change in velocity of said shaft to permit said flywheel to rotate relative to said shaft and move axially relative to said shaft,

brake means actuated by the axial movement of said flywheel, velocity responsive means,

and gearing means establishing a driving connection between said velocity responsive means and said flywheel whereby said flywheel can drive said velocity responsive means so that a predetermined velocity of said shaft causes axial movement of said flywheel, whereby axial movement of said flywheel and thus actuating of said brake can be effected by either a predetermined change in velocity or the attainment of a predetermined velocity of said shaft.

2. In a braking system,

a shaft drivingly connected to a rotary member, a flywheel,

means urging said flywheel to move with said shaft but responsive to a predetermined change in velocity of said shaft to permit said flywheel to rotate at a velocity different from the shaft,

brake means actuated by the flywheel upon said difference, motion multiplying means, and

velocity responsive means connected by said motion multiplying means to said flywheel, and responsive when reaching a predetermined velocity to cause a difference in velocity between said flywheel and said shaft, whereby to actuate said brake so that the brake actuation can be effected either by a predetermined velocity or by a predetermined change in velocity of said shaft.

3. In a braking system for a winch drum, a shaft drivingly connected to said drum, a flywheel,

means providing a rotary connection between said flywheel and said shaft and urging said flywheel to rotate with said shaft but responsive to a predetermined change in velocity of said shaft to permit said flywheel to rotate relative to said shaft and move axially relative to said shaft,

brake means actuated by the axial movement of said flywheel,

and velocity responsive means responsive to a predetermined velocity of said shaft to cause axial movement of said flywheel, whereby axial movement of said flywheel and thus actuating of said brake can be effected by either a predetermined change in velocity or the attainment of a predetermined velocity of said shaft.

4. A braking system as described in claim 3, in which the first named means provides a threaded connection between said flywheel and shaft and urges said flywheel to rotate with said shaft, but is responsive to a predetermined change in velocity in said shaft to permit said flywheel to thread along said shaft and hence move axially relative thereto.
